PHOTOCELL MULTIPLIER APPARATUS

Hans W. G. Salinger, Fort Wayne, Ind., assignor,
by mesne assignments, to Farnsworth Research
Corporation, a corporation of Indiana

Application September 29, 1944, Serial No. 556,434

7 Claims. (Cl. 250—41.5)

1

This invention relates to target-locating methods and devices, and particularly to systems of this character employing photocell multiplier tubes.

According to conventional practice photocell multiplier tubes of various types have been used to provide information regarding the location of a remote target in the form, for example, of a point of light. Generally, the tubes previously used have been of two classes. One type of tube is provided with a photoelectric cathode divided into separate areas of predetermined form such as quadrants of a circular area and has arranged cooperatively therewith an individual electron multiplier for each subdivision of the cathode area. The other type of tube employs a solid photoelectric cathode and a plurality of electron multipliers having anode structure of suitable configuration to divide the electron image as desired.

As is well known in the art, however, tubes of these types are capable only of providing information regarding the general location of the target. These tubes are incapable of supplying detailed information regarding the accurate location of the target with respect to a line of sight which conveniently may be arranged to coincide with the optical axis of the tube.

In all devices of this character employing photosensitive cathodes there always is present a so-called dark current. This is produced by a relatively small electron emission from the cathode surface even in the absence of light. Where it is desired to use a device of this character for the location of a point source of light, for example, in an otherwise completely dark image, it, therefore, is seen that there is difficulty in segregating the photoelectric currents resulting from the emission which occurs even in the absence of light and that produced by the projection of an optical image of the light source upon the cathode. The separation of these two currents, where the apparatus is operated as a direct current device, is particularly difficult if it is desired to obtain information with any great degree of accuracy, especially where the light from the target source is weak. In a system in which the light received from the target source is impulsive or is interrupted at a relatively rapid rate, the apparatus may be operated as an alternating current device and the separation of the intelligence signal from the dark current signal is a comparatively easy matter. But, obviously, in many cases the interruption of the light at the

2

source is inconvenient and sometimes absolutely impossible.

It is an object of the present invention, therefore, to provide a novel target-seeking device including a photocell tube for converting an image of the area including a target into electrical intelligence representative of the accurate location of the target with respect to a predetermined point in an optical system used in conjunction with the tube.

Another object of the invention is to provide a novel method of locating a target, whereby to develop electrical effects representative of the target location.

15. The apparatus in accordance with the present invention comprises a photocell multiplier tube having a photosensitive cathode which may be, but not necessarily, divided into a plurality of separate electron emissive areas. An individual electron multiplier may be provided in association with each of the segmented cathode areas. The optical system with which such a device is provided includes means for projecting an optical image upon the cathode of the target light source 20 in a manner to produce a substantially circular trace. The projecting means may include a lens which is mounted for eccentric rotation relative to the center of the cathode. Additionally, there is provided, in accordance with a novel feature 25 of this invention, means for intermittently interrupting the projected light. This interrupting means may consist of a pair of disks, each of which is provided with a plurality of alternate transparent and opaque areas. The disks should 30 be mounted between the cathode and the light source and should be adapted for relative movement in order to interrupt the light.

The method of locating the light target in accordance with this invention comprises, effecting a rotating projection upon a photosensitive cathode of a light spot representative of a target source. The light projection upon the cathode is interrupted at a predetermined frequency and the alternating component of the photoelectric 45 emission from the cathode resulting from the two foregoing steps is amplified so that it may be utilized to provide information indicative of the accurate location of the target light source with respect to a given reference axis.

50. For a better understanding of the invention, together with other and further objects thereof, reference is had to the following description, taken in connection with the accompanying drawing, and its scope will be pointed out in the appended claims.

In the accompanying drawing:

Fig. 1 is a diagrammatic representation of apparatus embodying the present invention;

Fig. 2 is a sectional view taken on the line 2—2 of Fig. 1, and illustrating one configuration of the photosensitive cathode, together with an associated electron multiplier arrangement in an embodiment of the invention in a preferred form;

Fig. 3 is a sectional view taken on the line 3—3 of Fig. 1, and illustrating the configuration of the lens supporting structure; and

Fig. 4 is a sectional view taken on the line 4—4 of Fig. 1, and illustrating the structure of one of the light interrupting members.

Having reference now to Fig. 1 of the drawing, the apparatus embodying the present invention includes a photocell multiplier tube, the electrodes of which are mounted within an evacuated envelope 11. In the illustrative form of the invention there is provided a photosensitive cathode 12 located adjacent one end of the tube envelope in such a manner that its sensitized surface faces the end of the tube. In this form of the invention the cathode comprises four substantially equal quadrant areas designated by the characters I, II, III and IV, and best illustrated in Fig. 2. Each of the quadrant areas of the cathode is distinct from the others. This arrangement may be provided in any conventional manner such as by setting separating strips between the quadrant areas or by cutting narrow slots in the cathode surface.

Associated with each of the quadrant areas of the cathode there is provided a multistage electron multiplier, the first stage electrode of each of which is located adjacent one segment of the sensitized surface of the cathode 12. For example, the multiplier associated with the cathode quadrant II has a first stage electrode 13 with the input opening thereof located adjacent to the peripheral edge of this cathode quadrant. In like manner, the first stage electrode 14 of the electron multiplier associated with the cathode quadrant IV is similarly located with respect to the peripheral edge of this portion of the cathode. Each of the multipliers may comprise as many secondary electron emissive electrodes, arranged in a conventional series manner as illustrated, or as otherwise desired, as may be needed to effect the required multiplication of the electron emission from the cathode. Each of the multipliers is provided adjacent the final secondary electron emissive electrode thereof with an electron collector electrode such as 15 and 16 respectively of the multipliers associated with the cathode quadrants II and IV.

As illustrated, each of the photocell electron multiplier units is connected to a source of energy for the impression of the required operating potentials upon the component electrodes. In the case of the unit including the cathode quadrant II, the energy source may be a battery 17 provided with a plurality of taps at appropriate points so that the desired voltages may be derived therefrom. Similarly, a battery 18 furnishes energy to the unit including the cathode quadrant IV. It is contemplated that, instead of employing separate sources of energy for each of the units comprising the apparatus embodying the invention, a single source may be employed with substantially equal facility. In such a case the connections of corresponding electrodes of the different units of the device may be made to the same points on the common energy source in a manner well known in the art. This latter type

of connection may be made most conveniently by interconnecting the corresponding multiplying electrodes within the tube, so that only one set of conductors need to be extended to the energy source. In the present case the cathode quadrant II is connected to the negative terminal of the battery 17. The first stage multiplier electrode 13 and succeeding multiplier electrodes are connected to points of increasing voltage on the battery 17 in a well known manner. The collector electrode 15 is connected through an output impedance such as a resistor 19 to the positive grounded terminal of the battery 17. In like manner the cathode quadrant IV is connected to the negative terminal of a battery 18 and the collector electrode 16 is connected through an output impedance such as a resistor 20 to the grounded positive terminal of this battery. In case a single energy source is used for the multiplying electrodes, it nevertheless will be necessary to separately connect the collector electrodes to their respective output impedances.

The alternating current components of the signal voltages developed in the output resistors 19 and 20, in a manner to be described, are impressed upon individual alternating current amplifiers 21 and 22, respectively. Condensers 23 and 24 provide the necessary alternating current coupling between the respective output resistors 19 and 20 and their associated amplifiers 21 and 22.

In order to project light coming from a distant target source P located at the left of the apparatus as shown in the drawing, there is provided an optical system which includes a condensing lens 25. This lens is supported in a circular disk 26 in such a manner that the lens is located eccentrically with respect to the axis through the center of the supporting disk. Also, rigidly mounted to the lens supporting disk 26 is another disk 27 which is provided with alternate transparent and opaque sectors. The configuration of the disk 27 and its relationship to the lens 26 is best illustrated in Fig. 3. This disk is provided within the area of the lens with a plurality of spaced transparent sectors such as 28 with which are alternated a plurality of spaced opaque sectors such as 29. These sectors radiate from the center of the disk. All portions of the disk outside of the lens area are opaque, as illustrated. The unitary structure comprising the two disks 26 and 27 and the lens 25 is arranged for rotation about the central axes of the two disks by any conventional means (not shown). In the present form of the invention, it is preferred to arrange the axis of rotation of the lens structure to coincide with the central axis of the tube through the center of the quadrant cathode 12.

There also is provided a disk 30 which may be located between the rotating lens structure and the tube cathode 12. The disk 30 is a stationary structure and is located coaxially with the disks 26 and 27. It also comprises a plurality of alternate transparent sectors 31 and opaque sectors 32 in like numbers and arrangement with respect to the center of the disk as those of the disk 27. In this case, however, the sectors extend to the peripheral edge of the disk 30, as illustrated.

Referring now to the operation of the described apparatus, assume that light coming from a distant target P is to be accurately located with respect to the central axis of the photocell multiplier tube. In the assumed instance, the target P is located somewhat above the line extend-

ing through the central tube axis. As the lens supporting disk structure is rotated about its central axis, and that of the tube, at a predetermined rate, the light from the target P is projected as a relatively small moving spot of light onto the photoelectric cathode 12. By reason of the eccentrically mounted lens 25, the path of the light spot on the cathode is circular, as indicated by the broken line 33 of Fig. 2. The center of the circular path 33 on the cathode represents the location of the target light source P with respect to the tube axis. There, of course, is not any visible indication of this actual target location on the cathode. However, for the purpose of clarifying this description the target location on the cathode is indicated in Fig. 2 by the point 34 which, it is seen, lies at a small distance directly below the center of the cathode in the quadrant IV. It lies below rather than above the cathode center by reason of the image inverting property of the lens 25.

The light which is projected onto the cathode 12 is interrupted at a predetermined rate by means of the continuously changing relationship of the disks 27 and 30. When the transparent sectors of these two disks such as 28 and 31 respectively are in register, light from the source P is projected onto some portion of the cathode. At an instant later when the transparent sectors such as 28 of the disk 27 are in register with the opaque sectors such as 32 of the disk 30, the light beam is interrupted and does not reach the cathode. It may be seen that the provision of a plurality of such alternate transparent and opaque sectors on the disks 27 and 30 will produce an interruption of the light beam at a rate determined by the number of disk sectors and the speed of rotation of the disk 27 relative to the fixed disk 30. The result then is a succession of light impulses projected onto the cathode along a circular path somewhat in the manner indicated by the broken line 33 of Fig. 2.

The electron emission from the cathode quadrant II, for example, may be amplified to any desired degree by the associated electron multiplier which includes the first stage electrode 13. The electron emission from this and all other cathode quadrants comprises a steady emission commonly called the dark current, plus an intermittent emission of somewhat greater intensity resulting from the light impulses projected onto this cathode quadrant from the target light source. There thus is developed in the output resistors such as 19 a signal voltage which has a steady direct current value representative of the so-called dark current cathode emission and, in addition, a superimposed pulsating voltage which represents the alternating current component indicative of the location of the target light source with respect to that particular cathode quadrant. By reason of the employment of the coupling condensers such as 23, between the respective output resistors and the associated amplifiers, there are impressed upon these amplifiers only the so-called alternating current components of the voltages developed in the output resistors. In this manner it is seen that the so-called dark current emission represented by the direct current component of the voltages developed in the output resistors is eliminated from the signals developed in the output circuits of the amplifiers. Obviously, the multiplier output impedances, herein represented by resistors 19 and 20, may instead comprise antiresonant circuit components tuned for response substantially

only at the light interruption frequency. In such a case the coupling condensers may be eliminated.

As indicated previously, a device of this character will be provided with an amplifier for each section of the cathode. In the embodiment of the invention chosen for illustration herein, a device having a quadrant cathode will be provided with four amplifiers similar to the amplifiers 21 and 22. The average output signal from any amplifier over a period of time is representative of the length of the arc of the circular trace 33 made by the projection of the light spot on the cathode quadrant associated with that amplifier. Obviously, the amplifier output voltage representative of the length of the arc of the trace 33 on a given cathode quadrant, when considered in relation to the voltages representative of the other arc lengths of the circular trace on the other cathode quadrants, is information which can be correlated, in a manner which subsequently will be described, to indicate the position of the target light source with respect to the center of the cathode. The cathode center, for convenience, is assumed to lie on the central axis of the tube.

As an example, consider the signal voltages which will be developed under the assumed conditions in the respective output circuits of amplifiers 21 and 22 as representative of the portions of the circular trace 33 projected onto the respective cathode quadrants II and IV. If the target light source is located as assumed in the position indicated by the point 34, it is obvious that the arc length of the trace 33 appearing in cathode quadrant IV will be considerably greater than that appearing in cathode quadrant II. Considering the periodic interruption of the light beam by the lens supporting disk 27 and the cooperating stationary disk 30, assume that, in the time the light projecting optical system is functioning to direct light onto the cathode quadrant II, there occur interruptions of the light beam resulting in the projection onto this cathode quadrant of ten light impulses. In like manner, assume that in cathode quadrant IV there are projected thirty such light impulses. Inasmuch as all of the light impulses are of equal duration and intensity, it follows that the total emission resulting from the light projection onto the cathode quadrant IV will be substantially three times greater than the total emission from the cathode quadrant II. It will be understood that the electron emission from the cathode areas referred to is that resulting from the projection of the optical image of the target light source onto the cathode and is in addition to the so-called dark-current emission.

After suitable multiplication by means of the described electron multipliers associated with each of the cathode quadrants, it is seen that the alternating current components of the signal voltages developed in the output resistors 19 and 20 will be so related that the energy impressed upon the amplifier 22 will be substantially three times greater than the energy impressed upon the amplifier 21. Similar conditions, of course, will obtain in the respective output circuits of these amplifiers.

In substantially the same manner, the amplifiers (not shown) associated with cathode quadrants I and III will produce in their respective output circuits signal voltages representative of the arc lengths of the circularly projected light path 33 appearing in these

quadrants. Therefore, the four amplifiers associated with the four quadrant areas of a photoelectric cathode will produce signal voltages from which may be derived, by any conventional means, information regarding the accurate location of the center point 34 of the circular light trace 31 relative to the center of the cathode. This information, of course, under the assumed conditions also will be representative of the accurate location of the target light source P relative to the central axis of the tube. As indicated, the means for utilizing the signal voltages derived from the amplifiers may be conventional and for this reason is not shown specifically herein for the reason that it comprises no part of the instant invention.

It follows, therefore, that the photocell multiplier tube may be oriented or aimed in a manner to bring the axis thereof in substantial alignment with the target light source P. In such a case, it is obvious that the center point 34 of the light trace 33, which then will be projected onto the cathode 12, will coincide with the center of the cathode at the intersection of the co-ordinate axes thereof. In such a case, the signal voltages derived from the output circuits of the respective amplifiers associated with the four cathode quadrants will be substantially equal. Therefore, these output voltages may be utilized in a manner to indicate that the circular light trace 31 is centered about the origin of a cathode axis.

It is contemplated to be within the scope of the instant invention that a photocell multiplier tube may be provided with a cathode divided into any desired number of segments, and not necessarily into quadrant areas, as illustrated. In such cases, the amplifiers associated with each of the cathode segments may be connected to suitable utilization circuits whereby the necessary comparisons between the respective output voltages may be made in order to produce the required information regarding the location of the target light source relative to a predetermined reference axis. Obviously, this reference axis need not necessarily coincide with the central or any other axis of the photocell multiplier tube. Also, it is considered that the instant invention is not limited necessarily to the employment of any particular type of electron multiplier. It is considered to be obvious that the electrode structure and arrangement of such multipliers may be substantially as desired to suit a particular type of tube. It also may be necessary in some applications to dispense entirely with electron multipliers used in cooperation with a photosensitive cathode. The emission from each cathode segment may, in such a case, be sufficient for employment directly in the production of signal voltages in an associated output impedance device. The invention also is considered to be of sufficient scope to include the interposition of the light-interrupting disks between the target light source and the lens 25, instead of in the locations illustrated herein.

While there has been described what, at present, is considered the preferred embodiment of the invention, it will be obvious to those skilled in the art that various changes and modifications may be made therein without departing from the invention, and therefore, it is aimed in the appended claims to cover all such changes and modifications as fall within the true spirit and scope of the invention.

What is claimed is:

1. In a target seeking device, a photosensitive

7
cathode, means including a rotating lens located in front of said cathode for projecting light from a target light source onto said cathode in a manner to produce a circular trace having a center located with respect to a predetermined point of said cathode representative of the target source location relative to said cathode point, and movable means located in front of said cathode for intermittently interrupting said projected light.

10 2. A target seeking device comprising, a photosensitive cathode divided into a plurality of electron emissive areas, means adjacent the respective emissive areas of said cathode for individually collecting the electron emission from each of said cathode areas, a lens located in front of said cathode for projecting light from a target light source onto said cathode and mounted for eccentric rotation relative to a predetermined point of said cathode, and rotating means located in front of said cathode for periodically interrupting said projected light.

15 3. A target seeking device comprising, a photosensitive cathode divided into a plurality of electron emissive areas, means adjacent the respective emissive areas of said cathode for individually amplifying the electron emission from each of said cathode areas, a pair of substantially identical devices each having a plurality of alternate transparent and opaque areas mounted 20 between a target light source and said cathode, said devices being movable relative to one another to interrupt light projected onto said cathode from said source, and a lens mounted between said source and said cathode and adapted 25 for eccentric rotation relative to the center of said cathode.

30 4. A target seeking device comprising, a photosensitive cathode divided into a plurality of electron emissive areas, an electron multiplier individual to and operatively positioned with respect 35 to each of said cathode areas, a pair of cooperatively arranged disks, each having a plurality of alternate transparent and opaque sectors mounted between a target light source and said cathode, said disks being rotatable relative to one another to interrupt the light projected onto said cathode from said source, and a lens mounted between said source and said cathode and adapted for eccentric rotation relative to the center of one of said disks.

40 5. A target seeking device comprising, a photosensitive cathode divided into quadrant electron emissive areas, a multistage electron multiplier individual to and operatively positioned with respect to each of said cathode areas, a pair of coaxially arranged disks each having a plurality of alternate transparent and opaque sectors mounted between a target light source and said cathode, one of said disks being stationary and the 45 other of said disks being rotatable about its center, and a lens mounted eccentrically relative to the centers of said disks between said source and said cathode and adapted for rotation about the center of said disks.

50 6. A target seeking device comprising, a photosensitive cathode divided into quadrant electron emissive areas, a multistage electron multiplier individual to and operatively associated with each of said cathode areas, an alternating 55 current amplifier capacitatively coupled to each of said multipliers, a pair of disks coaxially arranged with the center of said cathode and each having a plurality of alternate transparent and opaque sectors, said disks being mounted between a target light source and said cathode, one

of said disks being stationary and the other of said disks being rotatable about its center, and a lens mounted eccentrically relative to the centers of said disks between said source and said cathode and adapted for rotation by and with said rotatable disk.

7. The method of locating a target light source which includes the steps of, projecting light from said source upon a photosensitive cathode in a substantially circular path, interrupting said projected light at a predetermined frequency, and separately amplifying the resulting electron emission from individual areas of said cathode.

HANS W. G. SALINGER.
